UNITED STATES PATENT OFFICE.

FRANK B. DAVIDSON AND HARRY P. SHOTTS, OF MARSEILLES, ILLINOIS, ASSIGNEES
TO HOWE AND DAVIDSON COMPANY, A CORPORATION OF NEW JERSEY.

CARTON.

1,090,457.

Specification of Letters Patent. Patented Mar. 17, 1914.

Application filed December 6, 1911. Serial No. 664,257.

To all whom it may concern:

Be it known that we, FRANK B. DAVIDSON and HARRY P. SHOTTS, citizens of the United States, and residents of Marseilles, in the county of La Salle and State of Illinois, have invented certain new and useful Improvements in Cartons; and we do hereby declare that the following is a full, clear, and exact description thereof, reference being had to the accompanying drawings, and to the letters of reference marked thereon, which form a part of this specification.

This invention relates to improvements in paper boxes or cartons of that class in which the side and bottom walls thereof are provided with integral flaps which are interfolded and interlocked to form the end walls of the box.

This invention is illustrated in the accompanying drawings, as embodied in a box or carton of elongated shape, the ends of which are square and are formed by a plurality of interlocking flaps, and the top wall of which is formed by a flap that is adapted to be opened for inserting the contents of the box, but the invention may also be applied to cartons of other shapes and to cartons having but one wall that is formed by interlocking flaps.

The invention consists in the matters hereinafter set forth, and more particularly pointed out in the appended claim.

In the drawings—Figure 1 is a perspective view of a box or carton made in accordance with our invention; Fig. 2 is a perspective view of one end of the carton with the side and bottom walls of the box set up, but with the interlocking flaps opened outwardly away from their locking positions to more clearly show the construction thereof; Fig. 3 is a similar view showing in their closed positions all the end flaps but that carrying the locking-tongue and the locking-tongue partially inserted into the locking-slit that receives the same; Fig. 4 is an end view of the box with the several flaps in their partially interlocked positions. Fig. 5 is a view of one end of the blank from which the carton is made.

As shown in the drawings, the carton consists of a top wall a , two parallel side walls, a^1 , a^1 , a bottom wall, a^2 , and end walls a^3 , a^3 , the latter consisting each of a plurality of interlocking flaps. Each of said end walls comprises three flaps, to wit, a

flap a^4 connected with one side wall of the box, a flap a^5 connected with the other side wall thereof, and a flap a^6 connected with the bottom wall of the box.

The blank for forming the carton (indicated by A in Fig. 5) consists of connected parts a , a^1 , a^2 , a^4 , a^5 , and a^6 , corresponding with the parts of the box similarly lettered in the drawings. The flap a^4 on one of the side walls is provided with a tongue and the flap a^5 on the opposite side wall is provided with a locking slit or opening through which said tongue is inserted when the flaps are folded together and interlocked. The remaining or third flap a^6 is provided with a narrowed extremity, which when the flaps are folded, enters between the flaps a^4 and a^5 at one side of the center of the box end.

The top wall a of the box, in the particular construction shown in the drawings, is formed on one lateral edge of the blank and is connected with one of the side walls, so that its free edge may be swung upwardly from the other side wall to open the box, as indicated in Figs. 2, 3 and 4. The free edge of said top wall, moreover, as shown, is provided with a longitudinally extending narrow flap C which fits inside of the upper edge of the adjacent side wall of the box when the top wall is in its closed position. The upper edge of said side wall, which is engaged by the free edge of the top wall, is provided with a notch a^{18} , by which the finger may engage the said flap C of the top wall to facilitate opening the carton.

The flap a^5 is preferably made rectangular in form and of such width that when the blank is folded or in its closed position it engages at its upper and lower margins the top and bottom walls of the carton. The locking-slit in the said flap a^5 , marked a^7 in the drawing, extends from near the base of said flap, toward the free edge of the same.

The flap a^4 is provided with a locking tongue a^8 , which is so shaped and located that its free end or extremity is directed downwardly when the flaps are folded inwardly and is adapted to enter the said slit a^7 . Said slit a^7 is inclined downwardly, from its outer to its inner or locking end, which is engaged by the locking-tongue to hold the flaps a^4 and a^5 from spreading apart when the flaps are interlocked. The tongue-bearing flap a^4 is made of a width at its side which is attached to the side wall a^1 .

equal to the width of said side wall, and the tongue a^8 is located at or adjacent to the margin of said flap remote from said side wall. Said flap a^4 is notched at its lower edge or lowermost lateral margin to form said tongue, and the margin a^{11} of the flap at the inner side of said notch is oblique and extends diagonally from one lower corner of the flap to the base of the tongue a^8 .

10 As preferably constructed, the flap a^5 is provided above the slit a^7 , with two curved slits a^{17} , a^{18} , intersecting said slit near its ends, and forming a yielding section above said slit that may be easily pressed inward to facilitate the insertion of the end of the locking-tongue a^8 into said slit.

15 The flap a^6 , as shown, is made equal in width to the bottom wall of the carton at its point of attachment thereto, and its outer end is narrowed by cutting away the flap at one side only, so as to form an oblique edge a^9 and an edge a^{10} substantially parallel with the opposite edge of the flap, which latter is made perpendicular to the line at 20 which the said flap a^6 joins the bottom of the box, so that the outer part of said flap a^6 consists of a narrow part or tongue a^{19} , which, when the flaps are folded together, rests between the flaps a^4 and a^5 at one side 25 of the slit a^7 and tongue a^8 . The width of said tongue a^{19} is such and the slit a^7 is so located that when the flaps are folded together the side margin a^{10} of said tongue will approximately coincide with the inner 30 end of the said slit a^7 .

25 The tongue-bearing flap a^4 is made of such length that the outer margin of the tongue, when the flap is in its closed position, is located adjacent to the side wall a^1 , to which 35 the flap a^4 is attached. A flap B is preferably attached to the upper edge of the flap a^4 and is adapted to be folded inwardly beneath the top of the carton. The said tongue-bearing flap a^4 is provided with a 40 short slit a^{18} , which extends from the point at which the inner margin a^{14} of the locking-tongue intersects the oblique margin a^{11} of the said flap a^4 generally in a direction away 45 from the extremity or free end of the said 50 locking-tongue. As shown, said slit a^{18} is upwardly curved and its inner end is transverse to the margin a^{11} of the flap a^4 or generally parallel with the inner margin a^{14} of the tongue a^8 . The slit a^{18} thus arranged, 55 forms at the base of the locking-tongue, a concave edge, constituting in effect a hook or hook-like projection a^{16} adapted to engage the locking end of the locking slit. The curved slit a^{18} is so located with respect to 60 the slit a^7 that when the tongue a^8 is inserted in said slit and the flaps are brought together, or to their final position, and the sides of the carton are parallel with each other, the upper end of the inclined margin 65 a^{11} and the point of the projection a^{16} will

be at a considerable distance below the said slit a^7 , and the upper extremity of the curved slit a^{18} will be adjacent to or substantially coincide with the said slit a^7 . The inner end of the margin a^{14} of the tongue a^8 is so arranged relatively to the slit a^7 that it will engage the locking end of said slit, as the tongue a^8 is inserted in the slit, so that some degree of pressure and a slight distortion or yielding of the parts will be required in order that the projection a^{16} may be inserted through the slit, with the result that, as soon as the projection a^{16} enters the slit, it will spring into position for locking engagement with the locking end of said locking slit. Moreover, by reason of the relative location of the locking end of the slit a^7 , and the curved slit a^{18} , as above described, in the act of inserting the tongue a^8 in said slit a^7 , the hook-like projection a^{16} will be carried inwardly past the end of the slit a^7 , before the parts reach their final position, and the said point or angle of the projection will be at a distance below the said slit when the parts are in their final position. It follows that, after the parts are thus interlocked, the spreading apart of the flaps a^4 and a^5 will be restrained by the engagement of the locking end of the slit a^7 with the hook or hook-like projection formed by the curved slit a^{18} , at some point between its point or angle and the upper end of said curved slit.

65 The advantage gained by the features of construction described, is that the parts are brought into position to become with certainty interlocked before the flaps reach their final position in the closing of the flaps which form the box end, or when the flaps are not in fact brought accurately to such final position. In other words, if the flaps a^4 and a^5 are brought so nearly to their final position, in the act of inserting the tongue a^8 in the slit a^7 , that the point or angle of the projection a^{16} is carried inwardly through or below the said slit a^7 , the said projection will become engaged with the inner end of said slit, and the flaps cannot again be spread apart without breaking or distorting the parts.

It is, of course, to be understood that in setting up a carton of the kind described, before the filling of the same, or the insertion of its contents, it is not necessary that the box or carton should be brought to and held accurately in its rectangular form by the interlocking of its end flaps, for the reason that, after the carton is filled, the closing of its top and the application of the outer paper wrapper usually employed, will serve to fully close up the end flaps, and bring the side walls into parallel relation to each other. If, therefore, in the setting up of a carton made as described, through carelessness or inadvertence, the end flaps are not

brought accurately to their final relative positions, the end flaps α^4 and α^5 will become interlocked in a manner to prevent them from becoming detached from each other, and to prevent any material spreading apart of the side walls of the carton during the act of filling the same, while, at the same time, as soon as the carton is finally closed and the package is completed the said flaps will still be strongly and firmly interlocked.

The carton, made as herein described, has an advantage, as compared with the carton shown in the prior patent to Howe and Davidson, No. 825,539, issued July 10th, 1906, that will appear from the following: The carton of said prior patent is so made that it is necessary in all cases that the interlocking flaps be brought accurately or exactly to their final positions before any interlocking, adequate to prevent the subsequent spreading apart of the side walls, will take place, while in the case of the carton herein described, the end flaps will be sufficiently interlocked for all practical purposes, when the same are brought near, or only approximately to, the position that they occupy when the carton is finally closed. In other words, our present improvement enables the end flaps to be readily placed in interlocking relation, while insuring that the flaps will not become disconnected from each other through failure to bring the flaps accurately or exactly into a certain relative position in the act of folding the blank to form the carton.

It is to be understood that a box or carton embodying the features constituting our invention may differ in various features from

the construction illustrated in the accompanying drawings, and we do not therefore desire to be limited to the particular details of construction shown in said drawings, except so far as the same may be specifically set forth in the appended claim.

We claim as our invention:—

A paper box or carton having connected bottom and side walls, and provided on its side walls with interlocking flaps, and on its bottom wall with a flap adapted to be interposed between the interlocking flaps when the flaps are folded, one of said interlocking flaps being provided with a locking slit extending from its base toward its free end, and the other locking flap provided with an angular notch having obliquely arranged edges, and forming a laterally extending locking tongue for insertion in the locking slit of the other interlocking flap, with its oblique edge engaging the end of said locking slit, and a curved locking slit extending above the intersection of the oblique edges of said notch and forming a continuation of the oblique edge thereof, said slit being adapted to engage the end of the locking slit of the other interlocking flap and to lock said flaps together before the same are brought to their final relative positions.

In testimony, that we claim the foregoing as our invention we affix our signatures in the presence of two witnesses, this 28th day of November A. D. 1911.
